DESIGN FOR A CARD DISPLAY BOX

Ralph J. Gelinas, Cohasset, Mass., assignor to United-Rexall Drug Company, a corporation of Delaware

Application May 2, 1945, Serial No. 119,360

Term of patent 14 years

(Cl. D80—9)

To all whom it may concern:

Be it known that I, Ralph J. Gelinas, a citizen of the United States and a resident of Cohasset, Norfolk County, Massachusetts, have invented a new, original, and ornamental Design for a Card Display Box, of which the following is a specification, reference being had to the accompanying drawing, forming part thereof, in which

Fig. 1 is a side elevation of a card display box showing my new design;

Fig. 2 is a top plan view thereof;
Fig. 3 is a rear elevation thereof; and,
Fig. 4 is an isometric view thereof as seen from the right-hand front corner.

I claim:

The ornamental design for a card display box, substantially as shown.

RALPH J. GELINAS.
